UNITED STATES PATENT OFFICE.

LESTER W. MULVEY, OF NEWBURYPORT, MASSACHUSETTS.

CIRCUIT-BREAKER.

1,329,469.

Specification of Letters Patent.

Patented Feb. 3, 1920.

Application filed June 16, 1916. Serial No. 104,055.

To all whom it may concern:

Be it known that I, LESTER W. MULVEY, a citizen of the United States, residing at Newburyport, in the county of Essex, State 5 of Massachusetts, have invented certain new and useful Improvements in Circuit-Breakers; and I do hereby declare the following to be a full, clear, and exact description of the invention, such as will enable others skilled 10 in the art to which it appertains to make and use the same.

This invention relates to the class of circuit breakers, and pertains particularly to a device for controlling the aerial circuit in 15 a wireless system.

The primary object of this invention is to provide an automatic grounding device for wireless instruments.

It is furthermore an object to provide an 20 automatic circuit breaking device whose normal position is such that it will hold the receiving and sending sets of a wireless outfit in a ground circuit, but which may be actuated to connect the receiving and sending mechanism with the aerial, the circuit breaker returning to its normal position automatically when released.

More particularly, it is an object of the invention to provide a spring controlled device 30 which will normally hold a circuit breaker in such position that the operating circuit of the wireless set is disconnected from the aerial and connected to a ground circuit, but which may be depressed or 35 otherwise actuated against the action of the spring to hold the operating mechanism in circuit with the aerial, the spring controlled device returning to normal position as soon as it is released.

40 With the above and other objects in view, as will hereinafter appear, my invention will now be fully set forth and described, reference being had to the accompanying drawing.

45 In said drawings:—

Figure 1 is an elevation of one portion of the circuit shifting device,

Fig. 2 is a perspective view of a circuit reversing device,

50 Fig. 3 is a diagrammatic view of the electrical circuits in which my invention is inserted, and

Fig. 4 is a perspective view of a modified form of the invention.

Fig. 5 is an enlarged plan view of the 55 main switch mechanism.

Referring more particularly to said drawings 1 denotes a suitable base block upon which is mounted an oscillatory lever 2, said lever 2 being mounted on an intermediate insulated pin 3. Upon one end of said lever 2 is mounted a cross head 4 of copper or other material having suitable electrical conductivity, said cross head 4 having its ends shaped to engage between 65 the blades of the conductor terminals 5 and 6. The terminal 5 is connected to the wireless receiving and sending apparatus while the terminal 6 is grounded. Connected to the contact strip 4 by a suitable flexible connector 7 is the leading in wire of the wireless.

Mounted upon the opposite end of the lever 2 is a slightly curved rod 8, said rod being formed of soft iron so that its opposite end will provide cores for a pair of solenoids 9 and 10. Said solenoids are carried upon the base 1 and are positioned in opposite relation so that the ends of the iron bar 8 projects loosely into the solenoids and 80 can be affected thereby when one or the other is energized. Also carried by the lever 2 and extending beyond the bar 8 is an arm 11 whose upper end carries a contact block 12, said block 12 being arcuate 85 in shape and carrying a pair of spaced contact pieces 14 and 15. The block 12 rides upon the inner face of a fixed block 16 which is mounted upon the base and supports a pair of contact members 17 and 18. The 90 members 14 and 17 and 15 and 18 are arranged for alternate contact.

In Fig. 2, 19 indicates a footpiece which is pivoted at one end, the trunnions 20 carried by the foot-piece 19 being carried 95 in brackets 21. Below the foot-piece 19 is secured a spring 22, which normally expands to hold the free end of the foot-piece 19 in elevated position. At one side, the foot-piece 19 has secured thereto an arcuate block 100 23 which rides over a correspondingly shaped block 24 which rises from a base plate 25 rigidly mounted adjacent the foot-piece 19. The block 23 is provided with a pair of contact plugs 26 and 27 which are adapted to contact alternately with similar contact plugs 28 and 29 with which the block 24 is provided. The contacts 28 and 29 are

spaced apart in such relation to the contact plugs 26 and 27 that when the contacts 27 and 29 are in electrical connection, the contacts 26 and 28 are out of electrical connection, and vice versa.

Referring to the diagram of Fig. 3, it will be noted that the contacts 5 and 6 are connected respectively to the wireless set, and to the ground. The contact bar 4 is connected to the aerial 30, and is adapted, as it is swung into contact with either of the contacts 5 and 6 to connect the aerial to the wireless set or the ground. A battery 31 has one side connected in parallel to the contact plugs 28 and 29 of the block 24. The contact plugs 26 and 27 of the block 23 are connected respectively to the contacts 17 and 18 of the block 16, the conductors being led onto the base 1 by the binding posts 32. The opposite side of the battery is connected to the solenoids 9 and 10. The solenoids 9 and 10 respectively are connected to the pieces 14 and 15.

Referring to the modification shown in Fig. 4, the platform 33 represents the base upon which the operator's chair is located, said platform 33 being mounted and supported in practically the same manner as described for the foot-piece 19. Thus, when the operator occupies his place in front of the wireless instruments, the aerial is cut into the receiving circuit automatically by the operator's weight when he takes his seat. Conversely, when the operator rises, the apparatus is restored to normal condition by having the aerial set connected to the ground circuit.

In the operation of my improved mechanism, the normal position of the mechanism is, as hereinbefore stated that in which the ground circuit is connected to the wireless set, the circuits being then arranged as shown in the diagrammatic view. When it

is desired to cut in the aerial, and relieve the receiving and sending apparatus from the ground circuit, the foot pedal 19 is depressed against the action of the spring 22, at which time the contacts 26 and 28 are separated and the contacts 27 and 29 brought into electrical connection. This action sends the current from the battery through the plate 13 through the contact 18 and thus to the solenoid, which being thereby energized, draws the bar 8 downwardly so as to lift the contact member 4 into connection with the terminal 5, so that the receiving set is connected to the aerial.

What I claim as my invention is:

In a wireless telegraph set the combination with a ground terminal, a receiving set terminal and a leading in wire, of an oscillatory lever having a conductive head with which the leading in wire is connected and which head is movable upon oscillation of the lever to engage the receiving set and ground contacts alternately, the lever having armatures projecting from opposite sides, a solenoid surrounding each armature and under the alternate energization of which solenoids the lever may be oscillated, a pair of contacts carried by the lever and with which one terminal of each solenoid is electrically connected respectively, a source of electricity with one terminal of which the other terminal of each solenoid is electrically connected, spaced contacts disposed for engagement by the contacts of the lever, and a switch disposed to electrically connect said spaced contacts alternately with the other terminal of the source of electricity.

In testimony whereof, I affix my signature, in the presence of two witnesses.

LESTER W. MULVEY.
